SEWING MACHINE WORK-GUIDES

James E. Ackerman, Devon, and Henry C. Nissen, Stratford, Conn., assignors to The Singer Manufacturing Company, Elizabeth, N. J., a corporation of New Jersey

Application December 10, 1935, Serial No. 53,690

5 Claims. (Cl. 112—147)

This invention relates to improvements in work-guides for use in connection with sewing machines and has for its primary object to facilitate the production of stitched seams of different characters.

More specific objects of the invention are to provide means facilitating the formation and stitching of differently folded work-margins, and to provide for conveniently stitching folded work-margins at different distances from the outer fold edges thereof.

With the above and other objects in view, as will hereinafter appear, the invention comprises the devices, combinations and arrangements of parts hereinafter described in connection with the accompanying drawings which illustrate a preferred embodiment of the invention and in which:—

Fig. 1 is a top-plan view of a hem-folder and a double edge-folder, both in operative position upon a sewing machine bed-plate. Fig. 2 is a front elevation of the bed-plate and of the folder-elements positioned as shown in Fig. 1. Fig. 3 is a view similar to Fig. 1, but with the hem-folder 25 swung out of effective work-directing position. Fig. 4 represents a perspective view of the double edge-folder. Fig. 5 represents a perspective view of the hem-folder, a portion of the hem-folder shank being broken away. Fig. 6 represents a plan view of a portion of a shoulder-strap having successively edge-folded and hemmed margins. Fig. 7 represents a sectional view of the shoulder-strap substantially on the line 7—7 of Fig. 6. Fig. 8 represents a sectional view of the shoulder-strap substantially on the line 8—8 of Fig. 6.

The drawings illustrate the improvement as applied to a sewing machine having a work-support or bed-plate 1 upon which is suitably secured a throat-plate 2 apertured to receive a needle 3 carried by a vertically reciprocating needle-bar 4. Yieldingly opposed to the throat-plate 2 is a presser-foot 5, carried by a presser-bar 6 and having a needle-slot 7, the toe of the presser-foot 45 preferably being partly cut away to provide a guide-clearance notch 8.

Any suitable mechanism may be employed as complementary to the needle 3 in the formation of stitches, and the work may be advanced past the needle by any usual or suitable feeding mechanism, although the needle 3 is preferably included as a work-feeding element.

In its preferred embodiment, the work-guiding attachment comprises a holder-plate 9 pivotally secured by a screw 10 upon the work-support 1

at one side of the line A—B of seam formation. The holder-plate 9 has an ear 9' from which depends an anchor-pin 11 adapted to enter a suitable aperture provided in the work-support, the holder-plate being yieldingly held in anchored position by a coil-spring 12 interposed between the head of the pivot-screw 10 and said holder-plate.

Slidably mounted upon the holder-plate 9 is a carrier-plate 13 provided with guide-slots 14 which are elongated transversely of the line of seam formation, said guide-slots receiving the guide-screws 15 threaded into the holder-plate 9 and confining the carrier-plate 13 to right line movements lengthwise of the guide-slots 14.

Adjustably secured upon the carrier-plate 13 is the shank 16 of a double edge-folder 17, said shank 16 having a slot 18 elongated transversely of the line of seam formation to receive securing screws 19 and 20, and provide for adjustment of the edge-folder 17. The double edge-folder comprises an upper edge-turning scroll 21 adapted to downwardly fold back the margin of an upper ply of work material and a lower edge-turning scroll 22 adapted to upwardly fold back the margin of a lower ply of work material. The scrolls 21 and 22 are separated by a fold-margin guiding web 23 and are disposed in superposed relation to superimpose the marginal folds so that the folded margins extend in the same direction 30 from the fold-edges. The web 23 constitutes the roof portion of the lower scroll 22 and terminates at its free end in a downwardly bent and in-turned edge-guiding and fold-margin supporting lip 24. The web 23 is additionally provided at its 35 free end with an upturned ledge 25, Figs. 2 and 4, constituting an edge-guide for the underfolded margin of the upper work-ply. Mounted upon the ledge 25 is an apron 26 supporting the upper work-ply, said apron 26 being preferably stayed 40 by a suitable brace 27 extending from the under side of the apron to the downturned portion of the lip 24. The lower wall of the scroll 22 is preferably extended to provide a work-supporting apron for the lower work-ply. The superposed 45 scrolls 21 and 22 are soldered or otherwise suitably secured to an upstanding wall 28 carried by the folder-shank 16, said wall extending beyond the delivery ends of the scrolls at one side thereof to provide a guide for the superposed fold-edges of the work-plies. The wall 28 preferably 50 extends into the presser-foot guide-notch 8 to guide the work closely up to the stitching point.

The carrier-plate 13 has a rounded end 29 engaged by a cam 30 against which the carrier- 55

plate end 29 is yieldingly held by a suitable spring 31. The cam 30 is provided upon an auxiliary carrier-arm 32 pivotally secured for horizontal swinging movement upon the holder-plate 5 9 by a screw 33. An adjustable stop-plate 34 is provided with an upstanding ear 35 for engagement by the auxiliary carrier-arm 32 to limit the swing-out movement of the latter, said stop-plate 34 being secured to the holder-plate 9 by 10 screws 36 passing through a stop-plate slot 37 which is elongated transversely of the line of seam formation.

Adjustably disposed upon the auxiliary carrier-arm 32, for adjustment endwise thereof, is the 15 channeled shank 38 of a hem-folder 39, said shank 38 having a slot 40 elongated lengthwise of the shank and receiving the securing screw 41. The hem-folder 39, in the present instance, is adapted to turn back and also infold the lower 20 ply margin upon the upper face of said ply. To this end, the preferred form of hem-folder comprises a work-supporting apron 42 merging into a scroll having a concave wall 43 which curves upwardly, backwardly and then downwardly to 25 terminate in spaced relation to the apron 42. Carried by the downwardly extending end of the concave wall 43 is an infold-supporting wing 44 provided at the front end thereof, i. e., in front of the overhanging or backwardly turned portion 30 of the scroll, with an upwardly and reversely bent lip 45 arranged to form an arbor about which the work-margin is infolded.

When the hem-folder 39 is swung out so that its carrier-arm 32 engages the ear 35 of the stop-plate 34, the double edge-folder 17 is shifted by the cam 30 transversely of the line A—B of seam formation, into a work-directing position thereof illustrated in Fig. 3 of the drawings. In this position, the double edge-folder 17 may be employed 40 to inturn the overlying margins of superposed work-plies and to present the folded margins to the stitch-forming mechanism, the guide-flange 28 serving to direct the overlying fold-edges. It is commonly preferred to unite the inturned 45 fold-margins of superposed plies of material by a line of stitches disposed close to the fold-edges and, to this end, the above referred to operative position of the edge-folder 17 is preferably such that the guide-wall 28 is closely adjacent to 50 the seam line A—B.

When the hem-folder 39 is now swung into its effective work-directing position, as illustrated in Fig. 1 of the drawings, the turning movement of the cam 30 permits the spring 31 to shift the 55 edge-folder 17 laterally into a different work-directing position thereof, in which said folder 17 is disposed in alinement with the hem-folder 39 and between said hem-folder and the needle, whereby the lower scroll 22 of the edge-folder 60 may serve as a guide for the hem formed and delivered by said hem-folder 39.

The present invention is particularly adapted for use in seaming shoulder straps of overalls and the like, in which the shoulder straps comprise 65 extensions of different sections of the garment. Referring to Figs. 6, 7, and 8 of the drawings, the shoulder strap portion M of a garment-section is widthwise medianly doubled to form superposed strap-plies M, M', which are secured by a line of 70 stitches S adjacent to the fold-edge. Preparatory to uniting the superposed free edges of the strap, they are passed through the double-edge folder 17, in the swung-out position of the hem-folder 39, thereby to form superposed edge-folds 75 m and m' which are secured by a line of stitches

S' disposed closely adjacent to the fold edges. To provide for crossing the shoulder straps of the garment sections, the ply M' is suitably shaped, adjacent the juncture of the shoulder strap with the main portion of the garment-section, so that 5 the edge-fold m' is shorter than the edge-fold m of the ply M. When the stitching of the edge-folds m, m' has been completed substantially to the garment-section end of the ply M', the hem-folder 39 is swung into its effective work-directing 10 position in front of the edge-folder 17, which latter is thereby repositioned laterally concomitantly with the movement of the hem-folder into operative position. The margin of the lower 15 ply M is passed into the hem-folder 39 and the hem m² formed and delivered by the hem-folder is then guided to the needle by the edge-folding scroll 22 which is now in alinement with the hem-folder 39. The hem m² is guided to the needle so that it is secured by a line of stitches S² 20 which constitutes a continuation of the line of stitches S' but is spaced more widely from the outerfold-edge of the shoulder strap than is the line of stitches S', thereby to secure the hem-fold closely adjacent to the inner fold-edge 25 thereof.

The work-guides described, therefore, provide for successively forming and properly stitching work-margin edge-folds and hem-folds with facility and rapidity. It is to be understood, 30 however, that the invention in its broader aspects is not limited to work-guides having the specific constructive features herein described or to any particular order of use of the work-guides.

Having thus set forth the nature of the invention, what we claim herein is:—

1. In a sewing machine, the combination with 40 stitch-forming mechanism including a reciprocating needle, of a work-guide shiftable into and out of effective work-directing position, a second work-guide having an effective work-directing position between said first named work-guide and said needle, and means for concomitantly shifting said guides relatively to each other including connections between said guides for shifting 45 said second named guide into a different effective work-directing position.

2. In a sewing machine, the combination with 50 stitch-forming mechanism including a reciprocating needle, of a hem-folder shiftable supported for movement into and out of an effective work-directing position in front of said needle, an edge-folder shiftable into and out of an effective work-directing position between said hem-folder and said needle, and means for concomitantly shifting said hem-folder and edge-folder 55 relatively to each other.

3. In a sewing machine, the combination with 60 stitch-forming mechanism including a reciprocating needle, of an edge-folder having overlying edge-folding scrolls for individually folding adjacent margins of superposed work-plies, said edge-folder being shiftable from one to another of different work-directing positions in front of said needle, a hem-folder having an operative position in front of and in alignment with one of said edge-folding scrolls in one of the work-directing positions of said edge-folder, supporting means providing for shifting said hem-folder into a predetermined ineffective position, and operative 65 connections with said hem-folder supporting means for shifting said edge-folder into a different work-directing position concomitantly with the shifting movement of said hem-folder.

4. In a sewing machine, the combination with 75

stitch-forming mechanism including a reciprocating needle, of a laterally shiftable primary work-guide having a plurality of predetermined work-directing positions, an auxiliary work-guide pivotally supported for swinging movements from and into predetermined operative and inoperative positions, and connections between said guides effective to shift said primary work-guide from one to another of said predetermined work-directing positions thereof by a swinging movement of said auxiliary work-guide.

5. In a sewing machine, the combination with
stitch-forming mechanism including a recipro-

cating needle, of a primary work-edge folding guide having a plurality of predetermined work-directing positions, an auxiliary edge-folding guide movable relatively to said primary guide into and out of operative positions, and operative connections between said guides effective to shift said primary work-edge folding guide from one to another of said work-directing positions thereof by movement of said auxiliary guide relatively to said primary guide.
